UNITED STATES PATENT OFFICE.

ALLEN GORDON SMITH, OF LONDON, ENGLAND, ASSIGNOR TO S. SMITH & SONS (MOTOR ACCESSORIES) LIMITED, OF LONDON, ENGLAND.

DESIGN FOR A DASHBOARD FOR MOTOR-VEHICLES.

54,138.

Specification for Design.

Patented Nov. 4, 1919.

Application filed June 3, 1919. Serial No. 301,583. Term of patent 7 years.

To all whom it may concern:

Be it known that I, ALLEN GORDON SMITH, a subject of the King of England, residing at 179-185 Great Portland street, London, England, have invented a new, original, and ornamental Design for a Dashboard for Motor-Vehicles, of which the following is a specification, reference being had to the accompanying drawing, forming part thereof.

The figure is a plan view of the dashboard

for motor vehicles illustrating my new design.

I claim:

The ornamental design for a dashboard for motor vehicles, as shown.

A. GORDON SMITH.

Witnesses:

C. J. SAMPSON,
PHYLLIS HARRINGTON.
